UNITED STATES PATENT OFFICE.

ALBRECHIT GRAEF, OF NEW YORK, N. Y.

DESIGN FOR A RAZOR-BLADE.

SPECIFICATION forming part of Design No. 31,625, dated October 10, 1899.

Application filed September 9, 1899. Serial No. 730,026. Term of patent 7 years.

To all whom it may concern:

Be it known that I, ALBRECHIT GRAEF, a citizen of the United States, residing at New York, in the borough of Manhattan, State of New York, have invented and produced a new and original Design for Razor-Blades, of which the following is a specification, reference being had to the accompanying drawing, which represents the same in side elevation.

10 The leading features of my design for a razor-blade are a wreath-inclosed bust of a naval hero and at each side of the same radiating flags and cannons.

15 A represents a razor-blade, bearing upon it a bust B of a naval hero and a wreath C, in-

closing the bust, from which radiate at each side a number of flags D and emblematic representations of cannons E.

Having thus described my invention, I claim as new and desire to secure by Letters 20 Patent—

The design for a razor-blade, as herein shown and described.

In testimony that I claim the foregoing as my invention I have signed my name in presence of two subscribing witnesses.

ALBRECHIT GRAEF.

Witnesses:

PAUL GOEPEL,
M. HENRY WURTZEL.
